ELECTRIC SYSTEM, INCLUDING A VAPOR-ELECTRIC DISCHARGE DEVICE

Harold E. Edgerton, Belmont, Mass.

Original application August 16, 1933, Serial No. 685,501. Divided and this application August 5, 1946, Serial No. 688,406

9 Claims. (Cl. 315—261)

1

The present invention, though having fields of more general usefulness in electric systems, is particularly related to systems in which the discharge of a flash condenser is employed for such purposes as to produce a single flash or a repetition of flashes in flash-photography and stroboscopic work. The present application is a division of application Serial No. 685,501, filed August 16, 1933.

An object of the present invention is to provide a new and improved electric system of the above-described character.

Another object is to provide a new and improved condenser-charging system.

A further object is to improve the efficiency of condenser-charging systems.

Other and further objects will be explained hereinafter and will be particularly pointed out in the appended claims.

With the above ends in view, a feature of the invention resides in charging the condenser from a source of direct current through a series-connected reactor.

The invention will now be more fully explained in connection with the accompanying drawing, the single figure of which is a diagrammatic view of circuits and apparatus arranged and constructed according to one embodiment of the invention, illustrating a stroboscopic light source.

A flash condenser or capacitor 26, charged from a direct-current battery 102, is shown series-connected by wire conductors 8 and 10 in a discharge circuit to the anode 6 and the cathode 4 of a normally non-conducting gaseous-discharge or vapor-electric discharge device, such as a flash-lamp 2. The flashes are produced by discharging the condenser 26, after it has become charged, through the discharge circuit and through the gaseous medium of the lamp 2, between the anode 6 and the cathode 4. The condenser 26 may be charged to a voltage of from 200 to 2000 volts.

The lamp 2 is illustrated as of the mercury-arc type, the cathode 4 being in the form of a liquid pool of mercury. The lamp is shown as provided not only with the cathode 4 and the anode 6, between which the flash-producing current is sent through the mercury vapor of the lamp, but also with a starting control-grid electrode 100, situated around the glass, outside of the mercury pool 4.

2

A current-limiting charging impedance 35, which may be constituted of a wire conductor, comprising a combination of resistance and inductance, may be series-connected, in the charging circuit of the condenser 26, either in the wire conductor 10 or, as illustrated, in the wire conductor 8. The impedance 35 should be designed sufficiently large so that, after the discharge of the condenser 26 between the cathode 4 and the anode 6, further current flow between them will be prevented until after the space in the lamp 2 between the electrodes 4 and 6 shall have again become deionized. The impedance 35 should, however, be small enough to allow the condenser 26 to become recharged with energy from the battery 102 in time for the next flash. These ends may be attained by connecting a suitably reactive impedance 35 in series with the condenser 26 and the battery 102. The reactor 35 thus constitutes part of the means for charging the capacitor 26.

The impedance 35 thus inserted between the condenser 26 and its charging source 102 provides also for a proper charging rate of the condenser 26. Its size and characteristics should be determined by the characteristics of the flash lamp 2 or other apparatus and the desired time interval between the condenser discharges.

Because of the dielectric properties of the normally deionized mercury vapor in the space between the cathode 4 and the anode 6, if the mercury-arc tube 2 has been exhausted adequately, the battery 102 will charge the condenser 26 through the impedance 35 without any of its energy traversing that space. A difference of potential will therefore be established between the cathode 4 and the anode 6 during the charge of the condenser 26 before each flash.

A trip circuit is shown comprising a high-ratio step-up triggering flash transformer 30, a normally non-conducting mercury-vapor thyratron trigger tube 140, two impedances 31 and 33, shown as resistors, and a small trip condenser 28. The secondary winding 29 of the transformer 30 is connected between the starting electrode 100 and the cathode 4. The trip condenser 28 is shown charged from a second battery 101, through the impedance 31, which may perform a function similar to that of the impedance 35. The thyratron 140 and the primary winding 36 of the transformer 30 are connected in the discharge circuit.

of the trip condenser 28. The resistor 33, shown shunted across the trip condenser 28, allows a small current to flow, in order to maintain upon the control grid 50 of the thyratron 140 a voltage bias suitably negative with respect to the thyratron cathode 48. The anode of the thyratron 140 is shown at 52.

The trip circuit functions to discharge the trip condenser 28 through the mercury of the thyratron 140 and the primary winding 36 of the flash transformer 30. The direct-current energy of the second battery 101 becomes thus converted into sudden pulses in the primary winding 36. This discharge of the trip condenser 28 is effected at selected intervals, whenever it is desired to produce the flash, under the control of the thyratron grid 50. The potential on the grid 50, in turn, is shown controlled, for stroboscopic purposes, by an oscillator 62, through a transformer 64. The oscillator 62 supplies positive charges intermittently to the thyratron grid 50. This results in intermittently energizing the primary winding 36 to cause the starting electrode 100 intermittently to render the lamp 2 conducting. Other methods of controlling the grid 50 are disclosed in the said application.

The voltage pulses produced in the primary winding 36 in response to the discharge of the trip condenser 28 are conveyed, through the secondary winding 29 of the transformer 30, to the starting electrode 100 to impress a high-potential stimulus or charge thereon. The mercury vapor in the lamp 2 between the cathode 4 and the anode 6 becoming thereby ionized, the flash condenser 26 discharges suddenly through its discharge circuit. As the condenser 26 is connected between the cathode 4 and the anode 6, a very large current, over one thousand amperes, thereupon surges through the lamp 2 between the cathode 4 and the anode 6, producing a very brilliant intense quick flash of light. The operation of the lamp 2 from the discharge of the capacitor 26 is thus initiated by the control effected on the thyratron grid 50, energizing the starting electrode 100. The duration of the flash is of the order of microseconds, as determined by the size of the capacity 26, the voltage to which it is charged, the dimensions of the lamp 2, the impedance of the leads 8 and 10 connecting the condenser 26, and other factors. Under some conditions, the duration of the flash is less than one microsecond.

The instant when the flash occurs is thus accurately timed, without the aid of any switches in the high-voltage circuit, merely by having the oscillator 62 supply positive charges intermittently to the thyratron grid 50. This results in intermittently energizing the primary winding 36 to cause the starting electrode 100 to enable the condenser 26 to discharge intermittently between the cathode 4 and the anode 6, thereby producing intermittent flashes of light. Other methods of controlling the grid 50 are described in the said application.

The suddenly-applied relatively high voltages intermittently produced by the trip-potential surges on the grid 50 across the terminals of the secondary winding 29 will cause a bright cathode spot to form intermittently on the surface of the mercury cathode 4 and at the junction between the mercury and the inner wall of the glass tube. The gas in the tube becomes thus ionized. The bright spot constitutes a source of electrons in the vicinity of the cathode 4 that supplies electrons for the discharge of the condenser 26.

through the tube 2 between the anode 6 and the cathode 4.

Modifications will occur to persons skilled in the art, and all such are considered to fall within the spirit and scope of the invention, as defined in the appended claims.

What is claimed is:

1. A stroboscope comprising a source of supply of direct current, a reactor and a capacitor arranged in series and connected with said source, a vapor electric discharge device connected to be energized from said capacitor and provided with a control grid and means for controlling the charge on said grid.

2. A stroboscope comprising a source of supply of direct current, a reactor and a capacitor arranged in series and connected with said source, a vapor electric discharge lamp connected to be operated by the discharge from said capacitor, and grid control means for initiating the operation of said lamp.

3. A stroboscope comprising a source of supply of direct current, a reactor, a capacitor connected to be charged through said reactor from said source, a grid controlled vapor electric discharge device arranged to be energized by the discharge from said capacitor and means for intermittently supplying a positive charge to said grid.

4. A stroboscope having, in combination, a tube having an anode, a mercury-pool cathode and a starting electrode, a condenser connected between the anode and the cathode, means comprising a reactor for charging the condenser, a transformer having a primary winding and a secondary winding, means connecting the secondary winding between the cathode and the starting electrode, and means for intermittently energizing the primary winding to cause the secondary winding to energize the starting electrode intermittently and thereby to produce intermittently a source of electrons on the mercury-pool cathode, whereby the condenser will become enabled to discharge intermittently between the cathode and the anode to produce intermittently flashes of light.

5. A light-flash producer having, in combination, a normally non-conducting gaseous-discharge lamp having an anode, a cathode and a starting electrode and through which, when the lamp is conducting, a discharge may pass between the cathode and the anode, a condenser connected between the cathode and the anode, means comprising a reactor for charging the condenser, and means for energizing the starting electrode to render the lamp conducting, whereby the condenser will become enabled to discharge between the cathode and the anode to produce a flash of light.

6. A stroboscope having, in combination, a normally non-conducting gaseous-discharge lamp having an anode, a cathode, and a starting electrode and through which, when the lamp is conducting, a discharge may pass between the cathode and the anode, a condenser connected between the cathode and the anode, means comprising a reactor for charging the condenser, a transformer having a primary winding and a secondary winding, means connecting the secondary winding between the cathode and the starting electrode, and means for intermittently energizing the primary winding to cause the secondary winding to energize the starting electrode intermittently and thereby to render the lamp intermittently conducting, whereby the condenser will become enabled to discharge intermittently be-

tween the cathode and the anode to produce intermittently flashes of light.

7. In combination, a source of supply of direct current, a reactor and a capacitor arranged in series and connected with said source, a vapor-electric-discharge device connected to be energized from said capacitor and provided with a control grid and means for controlling the charge on said grid.

8. In combination, a source of supply direct 10 current, a reactor and a capacitor arranged in series and connected with said source, a vapor-electric-discharge lamp connected to be operated

by the discharge from said capacitor, and grid-control means for initiating the operating of said lamp.

9. In combination, a source of supply of direct current, a reactor, a capacitor connected to be charged through said reactor from said source, a grid-controlled vapor-electric-discharge device arranged to be energized by the discharge from said capacitor and means for intermittently supplying a positive charge to said grid.
